CLAIM

The ornamental design for a carry bag as shown and described.

DESCRIPTION

FIG. 1 is a top, front, right side perspective view of a carry bag showing the new design.

FIG. 2 is a front side view thereof.

FIG. 3 is a rear side view thereof.

FIG. 4 is a left side view thereof.

FIG. 5 is a right side view thereof.

FIG. 6 is a top view thereof; and,

FIG. 7 is a bottom view thereof.

In the Figures, the thinner broken lines show stitching which forms part of the claimed design. The thicker, shorter broken lines in the Figures show portions of the carry bag that form no part of the claimed design.

The stippling in the Figures is shown for purposes of illustrating shading of the claimed design.
